Primary Examiner — Rebekah A Caruso

(57) **CLAIM**

The ornamental design for a film applicator for mobile telephone as shown and described.

DESCRIPTION

1. Film applicator for mobile telephone

1.1 : Front

1.2 : Back

1.3 : Left

1.4 : Right

1.5 : Top

1.6 : Bottom

1.7 : Perspective

1.8 : Perspective

1.9 : Perspective

1.1 is a front view of a film applicator for mobile telephone showing our new design; 1.2 is a back view thereof; 1.3 is a left view thereof; 1.4 is a right view thereof; 1.5 is a top view thereof; 1.6 is a bottom view thereof; 1.7 is a bottom, front and right side perspective view thereof; 1.8 is a bottom, front and left side perspective view thereof; and 1.9 is a top, back and left side perspective view thereof.

1 Claim, 9 Drawing Sheets
